UNITED STATES PATENT OFFICE.

JOHN E. ELLIOTT, OF LOS ANGELES, CALIFORNIA.

ROTARY CORE DRILL.

Application filed May 13, 1922. Serial No. 560,760.

To all whom it may concern:

Be it known that I, JOHN E. ELLIOTT, a citizen of the United States, residing at Los Angeles, in the county of Los Angeles and State of California, have invented a new and useful Rotary Core Drill, of which the following is a specification.

This invention relates to an improved rotary core drill, particularly of the type by which a sample core is formed and extracted to determine the character of formation encountered.

An object of the invention is to provide a core drill in which the core is protected against flushing action of the circulating water and the cuttings of the core bit are directed into the path of the circulating water.

Another object is to provide a core drill in which the core will not become jammed or "froze" in the core barrel, and in which the core is subjected to a minimum amount of friction so as to prevent a burning of the core.

A further object is to provide a core drill having a central core bit and outer boring bits, and in which the cuttings of the core bit are directed in the path of the outer boring bits and the outer boring bits formed to urge the cuttings towards the outer periphery of the drill.

Various other objects and advantages will be more fully apparent from the following description of the accompanying drawings which form a part of this disclosure, and which illustrate a preferred form of embodiment of the invention.

Of the drawings:

Figure 1 is a vertical section through my improved core drill.

Fig. 2 is a bottom plan view of the cutter head removed from the body.

Fig. 3 is an elevation thereof.

Fig. 4 is a detail view illustrating the manner in which the cuttings are removed.

Fig. 5 is a detail view showing a modified form of cutter head.

In drilling wells, particularly oil wells, it is often desirable to obtain samples of the formation through which the drilling tool is passing for the purpose of determining the presence or absence of oil or other minerals and for obtaining a record of the various strata encountered, and in providing a core drill for this purpose which will successfully function in the various types of

formation certain requirements must be rigidly adhered to. As a drill of this character is ordinarily operated in the presence of circulating flushing water which carries the cuttings to the surface, it will be understood that the core, especially when operating in soft or sand formations, must be effectively protected against the flushing action of the water. This protection is best afforded by providing a central tubular core bit which extends beyond the outer boring bits and by so extending said core bit it becomes necessary to provide for an effective means for freely disposing of the cuttings of the core bit so its cutting action will not be hampered.

A further important requirement in a core drill resides in providing relief for the core immediately after it is formed or as soon after it is formed as is practical. There are two reasons for this requirement; one of which is based upon the fact that in deep wells where the formation is naturally under considerable load pressure, a core as soon as formed has a tendency to expand rather than shrink with the result that the core has a snug fit in the core bit and in the core receiving barrel where such barrel is of the same internal diameter as the core bit. This, during the continued rotation of the drill relative to the stationary core will create sufficient friction to cause a burning of the core and destroy its usefulness as an accurate sample of the formation and its contents. In addition to this, such frictional heat will expand the core and cause it to clog or become "froze" in the barrel.

Another reason for providing such relief is for the purpose of retaining the core within the drill, it being evident that after expanding in an enlarged core barrel it cannot again pass downwardly through the smaller core bit.

The core drill of the present invention fulfills each of the above requirements in the efficient and practical manner explained in connection with the following detailed description of the preferred form of embodiment illustrated in the drawings.

With particular reference to Fig. 1, the drill comprises a body 1 screw threaded on the lower end of a tubular shank 2, which may be of any desired length and following the usual practice may be considered as made up of several sections of drill pipe, a tool joint 3 being joined to the top of the shank

2 for connection with a string of drill tubing in the usual manner.

The body 1 has a central core receiving bore 4 and joined to the body in alignment with the bore 4 is a core barrel 5 extending upwardly into and spaced from the walls of the tubular shank 2. A check valve 6 carried by the upper end of the core barrel 5 permits water in said barrel to be expelled into the shank as the core moves into the barrel but prevents the flushing water entering the upper end of the barrel.

A tool head 7 is secured to the bottom end of the body 1 by bolts 8 or by any other suitable means and in general terms said tool head comprises a central tubular toothed core bit 9 having its bore aligned with and of a lesser diameter than the bore 4 of the body, and a plurality of outer cutters 10 surrounding the core bit 9.

The upper portion of the bore of the core bit 9 tapers to the larger diameter of the bore 4 and is provided with a serrated or roughened surface, preferably in the form of a plurality of upwardly directed teeth 11, such roughened or toothed tapered surfaces serving as a means of retaining the core within the tool.

As shown in the drawings, the teeth 12 of the core bit 9 extend beyond the cutters 10 and the bit between adjacent teeth is chamfered upwardly and outwardly as at 13 to provide a means for directing the cuttings from the teeth 12 upwardly and outwardly into the path of the outer cutters 10.

The cutters 10 have their cutting edges 14 angled outwardly and backwardly relative to the direction of rotation of the drill so as to urge the cuttings towards the outer periphery of the drill, each cutter and each of the teeth 12 of the core bit 9 being provided with proper relief rearwardly of their cutting edges to produce an efficient cutting action.

The body 1 and tool head 7 are provided with aligned ports 15-16, which communicate with the space between the core barrel 5 and the tubular shank 2 and direct the flushing water to the cutting edges of the outer cutters 10 where it will pick up and carry the cuttings in suspension upwardly between the tool and the wall of the well bore.

In Fig. 4, I have illustrated in a diagrammatic way, the operation of my improved core drill, and in such figure arrows 17 indicate the path of the cuttings from the core cutting teeth 12 as they are forced upwardly and outwardly into the path of the outer cutters 10, and arrows 18 indicate the path of the flushing water and the cuttings carried upwardly thereby, it being noted that the ports do not direct the water directly against the core bit 9 in a manner which might affect the core, but the water is

directed more or less vertically so that the core cuttings will not be picked up by the stream until fully ejected from the teeth 12 and crowded into the stream by subsequently formed core cuttings and by the action of the outer cutters 10.

In Fig. 5 I have illustrated a modified structure of tool head in which the core bit 9^a is formed as a separate shouldered member held in place by the head 7^a.

While the form of drill herein illustrated and described is well adapted to fulfill the objects primarily stated, it is to be understood that the invention is not to be limited in this regard, for it is susceptible of embodiment in various other forms all coming within the scope of the following claims:

1. In a core drill, a body having a tubular shank and a core receiving bore, a core barrel aligned with said bore and extending upwardly from the body within the shank, a central tubular core bit aligned with and of lesser internal diameter than the bore, the upper portion of the inner wall of the bit being beveled from its smaller diameter to the larger diameter of the bore and roughened to frictionally grip a core, and a plurality of outer cutters surrounding the core bit.

2. In a core drill, a body having a tubular shank and a core receiving bore, a core barrel aligned with said bore and extending upwardly from the body within the shank, a central tubular core bit aligned with and of lesser internal diameter than the bore, the upper portion of the inner wall of the bit being beveled from its smaller diameter to the larger diameter of the bore and provided with circular teeth for retaining a core, and a plurality of outer cutters surrounding the core bit.

3. In a core drill, a body having a tubular shank and a core receiving bore, a core barrel aligned with said bore and extending upwardly from the body within the shank, a plurality of outer cutters carried by the body, and a central tubular core bit aligned with the bore and provided with cutting teeth extended below the outer cutters, the core bit being chamfered upwardly and outwardly between the cutting teeth with said chamfers extending above the lower edge of the outer cutters.

4. In a core drill, a body having a tubular shank and a core receiving bore, a core barrel aligned with said bore and extending upwardly from the body within the shank, a plurality of outer cutters carried by the body, and a central tubular core bit aligned with the bore and provided with cutting teeth extended below the outer cutters and chamfered to direct cuttings upwardly and outwardly into the path of the outer cutters.

5. A cutter head for rotary core drills, comprising a plurality of circularly disposed

- outer cutters, and a central tubular core bit provided with cutting teeth at its lower end, the teeth projecting below the outer cutters and the bit between the teeth being chamfered outwardly and upwardly beyond the lower edges of the outer cutters to direct cuttings into the path of the outer cutters.
6. In a core drill adapted for use on the lower end of a rotating shaft, tubular members providing a core receiving chamber having the lower end thereof of reduced diameter for a relatively short distance, and flared upwardly and outwardly to substantially the diameter above said reduced portion, the flared portion of said core receiving chamber being equipped with circular teeth to form a gripping means to prevent the dropping of a core from said chamber, and cutters for forming a core.
10. 7. In a core drill adapted for use on the lower end of a rotating shaft, tubular members providing a core receiving chamber having the lower end thereof of reduced diameter for a relatively short distance and flared upwardly and outwardly to substantially the diameter above said reduced portion, the flared portion of said core receiving chamber being equipped with circular teeth to form a gripping means to prevent the dropping of a core from said chamber, and cutters for forming a core.
15. Signed at Los Angeles, Calif., this 1st day of May, 1922.

JOHN E. ELLIOTT.
